CIGARETTE NOVELTY

Waldemar Walter Miller, Henderson, Nev.

Application February 10, 1950, Serial No. 143,443

4 Claims. (Cl. 272—27)

1

This invention relates to a cigarette novelty and has for an object to provide a novelty or toy which looks like an opened package of cigarettes of any popular brand and is used as a harmless practical joke.

A further object of this invention is to provide a harmless practical joke type of novelty made up in the form of an imitation package of cigarettes.

A further object of this invention is to provide an imitation cigarette pack inexpensive to manufacture and sell and useful at parties for causing laughter.

With the foregoing and other objects in view, as will hereinafter become apparent, this invention comprises the combinations, constructions and arrangement of parts hereinafter set forth, claimed and shown on the accompanying drawings, wherein

Fig. 1 is a perspective view of the imitation cigarette pack of this invention.

Fig. 2 is a sectional view on line 2—2 of Fig. 1, and

Fig. 3 is a sectional view on line 3—3 of Fig. 2.

There is shown at 10 the imitation cigarette pack of this invention which consists of a container 11, the outside of which has a wrapping decorated to imitate any popular brand of cigarettes as at 12. This container 11 is provided with an opening 13 in one corner thereof similar to the usual opening made in a real pack of cigarettes when a cigarette is to be extracted therefrom. Visible through this opening 13 are a number of real or dummy cigarette ends 14 and a further dummy cigarette 15 extending just enough beyond the opening 13 to be visible and capable of being grasped by the finger of the victim when he is being offered an opportunity to take a cigarette from out of the package. This dummy cigarette 15, while finished to resemble a real cigarette, actually is the end of a piece of rubber tubing 16 whose other end 17 is secured to and curled about a cylinder 18 within which there is secured a coiled spring 20 whose inner end is secured about a hollow stanchion 21 fixed in the pack housing 11. The coil spring 20 is so arranged that it permits the cylinder 18 to be rotated and allow the dummy cigarette end 15 to be withdrawn from the pack a distance at least equal to the length of a cigarette that would be contained in a package of the same size.

Extending through one end of the hollow stanchion 21 is the stem 22 of a button 23 which is concealed and invisible within the pack wrapping 12. This stem 22 includes a cross-pin 24

2

movable in a pair of diametrically opposite slots 25 in the stanchion 21 extending between the inner side of the pack container 11 and the adjacent side of the cylinder 18. A small coil spring 26 encircles the stanchion 21 and is biased between the pin 24 and the inside of the container 11.

The side 19 of the cylinder 18 includes a number of struck-out ratchet teeth 27 so inclined 10 that when the cylinder is rotated in the direction to permit withdrawal of the dummy cigarette end 15, the ratchet teeth slide past the pin 24 on the button stem 22, but prevent rotation of the cylinder in the opposite direction. However, 15 pressing the concealed button 23 inwardly moves the holding pin 24 beyond the ends of the ratchet teeth 27 thereby permitting the coil spring to rotate the cylinder 18 and draw the dummy cigarette back into the pack.

20 In operation, the jokester may offer a cigarette to his victim with the dummy 15 in either the fully extended position as shown in Fig. 1 or the partly extended position shown in Figs. 2 and 3. In the fully extended position, the jokester, by 25 pressing the button 23 just as the victim is about to or has barely grasped the dummy 15, causes the cigarette to disappear within the pack. In the partly extended form, the victim is permitted to take the dummy 15 while the jokester holds 30 the pack, and then when the cigarette has been partly extracted, the jokester jerks the pack slightly and presses the button, thus removing the dummy from the victim's hand and causing it to disappear within the pack.

35 A suitable stop 29 is provided between the housing and the cylinder limiting its retracting movement to an amount that will cause the end of the dummy 15 to remain at least very slightly extended beyond the ends of the other dummy 40 cigarettes 14.

While the preferred form of this invention has been thus set forth and disclosed, it will be understood that this invention is not limited to the particular details of construction and arrangements or form hereinbefore disclosed, but that changes may be made in the invention within the scope of what is hereinafter claimed.

Having thus set forth and disclosed the nature of this invention, what is claimed is:

50 1. A practical joke cigarette novelty comprising an imitation open cigarette pack, a retracting mechanism mounted within said pack, an extendable cigarette dummy secured to said retracting mechanism, mechanism tending to hold 55 said retracting mechanism against retracting

movement, and means for releasing said holding mechanism causing said dummy cigarette to be retracted.

2. A practical joke cigarette novelty comprising an imitation open cigarette pack, a rotatable retracting mechanism mounted within said pack, a cigarette dummy secured at one end to said retracting mechanism, its other end being extendable through the pack opening, said mechanism including means permitting said mechanism to rotate in an extending direction, ratchet mechanism tending to hold said retracting mechanism against retracting movement, and means for releasing said ratchet mechanism causing said retracting mechanism to retract said dummy cigarette.

3. A practical joke cigarette novelty comprising an imitation open cigarette pack, a plurality of cigarette ends visible through the opening in the pack, a rotatable retracting mechanism mounted within said pack, an extendable cigarette dummy secured to said retracting mechanism, said mechanism including means permitting said mechanism to rotate in a cigarette dummy extending direction, ratchet means tending to hold said retracting mechanism against retracting movement, and manually operable

5
10

means for releasing said ratchet means causing said retracting mechanism to retract said dummy cigarette.

4. A practical joke cigarette novelty comprising an imitation open cigarette pack, a retracting mechanism mounted within said pack, an extendable cigarette dummy secured to said retracting mechanism, means tending to hold said retracting mechanism against retracting movement, and means for releasing said holding means causing said dummy cigarette to be retracted.
